United States Patent Office

Des. 194,134
Patented Nov. 20, 1962

194,134

PHOTOGRAPHIC COPYING APPARATUS OR THE LIKE

Joseph H. Wally, Jr., Shawnee Missions, Kans., assignor to Western Blue Print Company, Kansas City, Mo., a corporation of Missouri

Filed Nov. 30, 1961, Ser. No. 67,753

Term of patent 14 years

(Cl. D61—1)

FIG. 1

The dominant features of the design reside in the portions shown in full lines.

I claim:
The ornamental design for a photographic copying apparatus or the like, substantially as shown and described.
